VARIABLE PITCH AIRPLANE PROPELLER

Walter S. Taber, Honolulu, Territory of Hawaii

Application April 5, 1938, Serial No. 200,110

6 Claims. (Cl. 170—163)

(Granted under the act of March 3, 1883, as
amended April 30, 1928; 370 O. G. 757)

The present invention relates to variable pitch propellers and it has a particular relation to airplane propellers in which the pitch of the blades can be varied at will while the aircraft is in flight.

One of the objects of the invention is the provision of a propeller of the character described which embodies a hub having an axially arranged member rotatably mounted therein provided with a semi-spherical surface in which one or more coaxial helical threads or cam grooves having an equal pitch are formed for operative engagement with the root portions of one or more propeller blades rotatably mounted in the hub and by means of which the blades may be simultaneously rotated to vary the pitch thereof the desired degree.

Another object of the invention is the provision of a variable pitch propeller in which the several blades may be adjusted to alter their pitch with exactitude and which will maintain their adjustment without additional locking means.

A further object of the invention is the provision of a propeller in which the several blades are staggered to offset axially with respect to one another so as to rotate in different spaced parallel planes, thus cutting through and exerting a propelling or impelling action against different bodies of the air, water or other fluid medium with which they are in contact.

With these and other objects in view, as well as other advantages that may be incident to the use of the improvements, the invention consists in the parts and combinations thereof herein-after set forth and claimed, and with the understanding that the several necessary elements constituting the same may be varied in proportion and arrangement without departing from the nature and scope of the invention, as defined in the appended claims.

40 In order to make the invention more clearly understood, there are shown in the accompanying drawings, means for carrying the invention into practical use, without limiting the improvements in their useful application to the particular construction, which, for the purpose of explanation, have been made the subject of illustration.

In the accompanying drawings:

Fig. 1 is a view partly in front elevation and partly in vertical transverse section taken substantially on line 1—1 of Fig. 2;

Fig. 2 is a vertical longitudinal sectional view taken on line 2—2 of Fig. 1;

Fig. 3 is a view partly in front elevation and partly in vertical transverse section taken substantially on line 3—3 of Fig. 4; and

Fig. 4 is a vertical longitudinal sectional view taken on line 4—4 of Fig. 3.

Referring to the drawings, and particularly to Figs. 1 and 2 thereof, an airplane propeller embodying the present invention, is shown as comprising a hub, indicated as an entirety at 10, and which in turn comprises two hollow complementary rearward and forward members 11 and 12 respectively, secured together by bolts 13. The members 11 and 12 are formed with opposed sleeves 14 and 15 having a scarf joint 16 therebetween adapted to be mounted on the crank or drive shaft 17 of an engine, not shown. The sleeve 14 is keyed to the shaft 17 by means of a plurality of splines 18 formed on the sleeve and on the shaft and is held in abutting engagement with a shoulder 19 on the shaft by a nut 20 which is threaded onto the extreme forward end of the shaft 17 for engagement with the forward member 12 of the hub.

The hub 10 is also provided with a plurality of radially extending sockets 27 each being formed by complementary portions 28 and 29 of the members 11 and 12. Mounted for rotation within each of the sockets is a sleeve 31 formed at its inner end with an annular flange 32 for engagement with a shoulder 33 formed adjacent to the inner terminus of the socket and with internal screw threads 34 for engagement by corresponding screw threads on the root portion 35 of a propeller blade. The outer end of the sleeve 31 is formed with a plurality of slits 36 to provide a plurality of contractable outwardly tapered fingers 37 each of which is formed with inwardly extending projections 38 for engagement with notches 39 formed on the root 35 of the blade. These fingers are flexed inwardly so as to hold the projections 38 in interlocking engagement with the notches 39, by means of a frusto-conical nut 40 which is threaded onto the fingers 37 and 40 into abutting engagement with a shoulder 41 on the outer end of the socket 27. By means of this construction the sleeve 31, root 35 and nut 40 rotate in unison but are prevented from radial displacement from the socket 27 by the flange 32 and nut 40. The sleeve 31 is also formed at its inner end with an arm 42 which extends in a radial direction with respect to the axis of rotation of the sleeve and which is formed at its outer end with segmental worm teeth, or gear 43, the purpose of which will presently be described.

A spherical gear 44 is housed within the hub 10 for intermeshing engagement with the segmental worm 43 and is formed with integral circumferential flanges 45 and 46 on each side of

which are rotatably mounted on bearing rings 47 and 48 carried by the sleeve portions 14 and 15 of the hub 10. The flange 45 is formed with a worm gear 49 for intermeshing engagement 5 with a worm 50 which is fixed to a shaft 51. This shaft is journalled in bearings 52 and 53 mounted in an enlargement 54 formed on the inner portion 11 of the hub 10 and closed at its outer end by a screw plug 55. A worm gear 56 10 is fixed to the shaft 51 and is driven by a worm 57 fixed to a countershaft 58. This shaft is journalled in bearings 59 mounted in a transverse extension 60 of the enlargement 54 which is closed at its rear end by a screw plug 61. The 15 shaft 58 is at times intermittently rotated, in order to adjust the pitch of the propeller blades, by means of a jaw clutch mechanism comprising a member 62 keyed to the shaft 58 and a member 63 freely mounted on the shaft 58 but 20 held in driving engagement with the member 62 by a spring 64 interposed between the member 63 and a nut 65 threaded onto the rear extremity of the shaft 58. A star wheel 66 is fixed to the clutch member 63 for engagement with upper 25 and lower stops 67 and 68 formed on a vertical, reciprocable slide 69. This slide is suitably mounted on the engine frame and may be actuated by the pilot through the medium of a jointed rod or flexible cable connection, not shown.

30 *Operation.*—When the slide 69 occupies the intermediate position shown the star wheel 66 will pass between the stops 67 and 68 and no motion will be transmitted to the associated reduction gearing and spherical gear 44, thus 35 maintaining the propeller blades at a certain angle of pitch. If, however, the pilot should desire to vary the pitch of the propeller blades, he shifts the slide 69 upwardly or downwardly, as the case may be, so as to move one or the 40 other of the stops 67 or 68 into the path of movement of the revolving star wheel 66. This will cause the rotation of the reduction gearing in the desired direction and a corresponding rotation of the spherical gear 44, which through the 45 medium of the segmental worms 43 and arms 42 will turn the blades to the desired angle of pitch. If the pilot should inadvertently hold the stops in engagement with the star wheel until the pitch of the propeller approaches a dangerous 50 or undesired angle, the motion of the parts will automatically be arrested by the arms 42 engaging either of two stops 70 carried by the hub 10, one on each side of the arms 42. When the mechanism is thus locked against rotation, 55 breakage of the parts or stripping of the gears is prevented by the slipping of the clutch members 62 and 63 relative to one another.

In Figs. 3 and 4 there is illustrated another form of the invention wherein the hub 71 comprises an outer substantially cylindrical portion 72 formed with a concentric inner sleeve portion 73 adapted to be keyed to the crank or drive shaft 74 of an engine; and forward portion 75 formed with an inner sleeve portion 76 adapted 60 to be screw threaded onto the forward end of the drive shaft 74 and engaging the end of the sleeve portion 73 at a scarf joint 77. The portion 75 of the hub is also formed with an extreme forward cylindrical portion 78 for housing 65 an electric motor 79 hereinafter to be described, and with a discoidal portion 80 adapted to be secured to the forward end of the portion 72 by bolts 81.

The hub 71 is provided with a plurality of 70 radially extending sockets 82, each being stag-

gered or offset in an axial direction with respect to one another and within which the root portion 83 of a propeller blade is rotatably mounted. The blades are each prevented from radial displacement by means of a ring or collar 84 which is screw threaded onto the inner extremity of the root 83 and which is formed with two annular shoulders 85 for abutting engagement with corresponding shoulders formed in the hub. A split frusto-conical nut 86 is screw threaded 10 onto the socket 82 and is clamped thereon by bolts 87. These nuts form bearings for the blades within which they rotate when adjusted to vary their pitch. The collars 84 are each formed with an arm 88 which extends in a radial direction with respect to its axis of rotation and which has a stud 89 screw threaded into its outer extremity for engagement with a spiral cam groove 90 formed in a spherical cam 91. The cams 91 are preferably formed integrally 15 with one another and are rotatably mounted upon the sleeve portions 73 and 76 of the hub in alinement with the sockets 82. The forward cam 91 is formed with an internal worm gear 92 which meshes with and is driven by diametrically disposed pairs of worms 93. The worms of each pair are fixed to the ends of a shaft 94 which is journalled in bearings 95 on the sleeve portion 76 of the hub and which is rotated by a worm wheel 96 fixed thereto between the worms 30 93. This worm wheel is in turn driven by a worm 97 which is fixed to the rotor shaft 98 of the motor 79. The shaft 98 is journalled at its rear end in a bearing 99 carried by the portion 76 of the hub and at its forward end in a bearing 100 carried by a bracket 101 screw threaded onto the forward end of the cylindrical portion 78 of the hub. The stator of the motor 79 is carried by the portion 78 of the hub and is rotatable bodily therewith, being prevented from displacement by screws 102. This portion of the mechanism is enclosed by a spinner or casing 103 which is fixed to the plate 80.

The motor 79 is preferably of the synchronous reversible type energized by electric current 45 supplied through wires 104 connected with slip rings 105 mounted on the rear end of the member 73 of the hub and controlled from a dial on the instrument board. The control is such that when it is desired to turn the blades of the propeller to a certain pitch the dial is turned to a point indicating such pitch. This will cause the motor to rotate until it has turned the blades sufficiently and then automatically stop. The dial is provided with limit switches which control 50 the range within which the blades may be turned. This automatic control may be of any well known type and therefore has not been explained in detail.

The mechanism hereinabove described may be 55 modified in proportion and arrangement of the parts without departing from the nature and scope of the invention as defined in the appended claims.

The invention described herein may be manufactured and used by or for the Government of the United States of America for governmental purposes without the payment of any royalties thereon or therefor.

I claim:

1. A variable pitch propeller comprising a hub, a plurality of blades having their root portions mounted in said hub for rotation about radially extending axes and in axially offset relation along said hub, a plurality of coaxially arranged 75

5 spherical cams rotatably mounted in said hub, one associated with each of said blades, an arm fixed to the root portion of each of said blades and extending partly around the associated cam for operative engagement therewith, and means for rotating said cams to rotate said arms and blades about said axes to vary the pitch of said blades.

10 2. A variable pitch propeller comprising a hub, a plurality of blades having their root portions mounted in said hub for rotation about radially extending axes and in axially offset relation along said hub, a plurality of coaxially arranged spherical cams rotatably mounted in said hub, one associated with each of said blades, an arm fixed to the root portion of each of said blades and extending partly around the associated cam for operative engagement therewith, and a reduction gear train for rotating said cams to rotate said arms and blades about said axes to vary the pitch of said blades.

15 3. A variable pitch propeller comprising a hub, a plurality of blades having their root portions mounted in said hub for rotation about radially extending axes and in axially offset relation along said hub, a plurality of coaxially arranged spherical cams rotatably mounted in said hub, one associated with each of said blades, an arm fixed to the root portion of each of said blades and extending partly around the associated cam for operative engagement therewith, and an electric motor housed within said hub for rotating said cams to rotate said arms and blades about said axes to vary the pitch of said blades.

20 35 4. A variable pitch propeller comprising a hub, a plurality of blades having their root portions mounted in said hub for rotation about radially extending axes and in axially offset relation along said hub, a plurality of coaxially arranged spherical cams rotatably mounted in said hub, one associated with each of said blades, an arm fixed

to the root portion of each of said blades and extending partly around the associated cam for operative engagement therewith, an internal worm gear fixed to said cams, ellipsoidal worms meshing with said worm gear at intervals there-around, and means for rotating said ellipsoidal worms to transmit rotary movement to said cams, and blades to vary the pitch of the latter.

5 10 5. A variable pitch propeller comprising a hub, a blade having its root portion mounted in said hub for rotation about a radially extending axis, a spherical worm having threads of equal pitch extending substantially throughout its spherical surface rotatably mounted in said hub, an arm fixed to the root portion of said blade and having a worm gear segment thereon intermeshing with said spherical worm, an external worm gear fixed to said spherical worm coaxially thereof, a tangentially arranged worm intermeshing with said worm gear for rotating the same and said spherical worm to rotate said arm and blade about said axis to vary the pitch of said blade, and means for rotating said worm while the propeller is rotating.

15 20 25 30 35 40 6. A variable pitch propeller comprising a hub, a blade having its root portion mounted in said hub for rotation about a radially extending axis, a spherical worm having threads of equal pitch extending substantially throughout its spherical surface rotatably mounted in said hub, an arm fixed to the root portion of said blade and having a worm gear segment thereon intermeshing with said spherical worm, an external worm gear fixed to said spherical worm coaxially thereof, a tangentially arranged worm intermeshing with said worm gear for rotating the same and said spherical worm to rotate said arm and blade about said axis to vary the pitch of said blade, and means operable by the rotation of the propeller for rotating said worm.

WALTER S. TABER.
